CROSS-ADDING ACCOUNTING MACHINE AND PROGRAMMING MEANS THEREFOR

James W. Bryce, Glen Ridge, N. J., assignor to
International Business Machines Corporation,
New York, N. Y., a corporation of New York

Application October 1, 1937, Serial No. 166,820

7 Claims. (Cl. 235—61.8)

This invention relates to improvements in cross-adding machines and more particularly to such machines of the record controlled and record making type. Cross-adding machines are now in general use and their construction is such that there may be some diversity in the different calculations which can be performed by the machine. The extent of diversity of calculations which such form of machines are capable of performing is, in a measure, dependent upon the number of machine cycles available for successive transfer of amounts from accumulator to accumulator and the number of problems also depend, to a certain extent, upon the number of operating initiating controls and entry and transfer directing controls which are provided. Heretofore in previous commercial machines the construction was such that there were only a certain number of machine cycles available for transferring operations. The entry of transfer directing controls were also to a considerable extent limited.

The present invention has for its general objects the provision of a machine which is very much more flexible in the variety of cross-adding operations which can be performed by the machine and the flexibility of the machine for the performing of different calculations is under the control of the operator instead of being initially built in the machines at the factory.

A further object of the present invention is to provide a construction affording a greater number of cross-adding results than obtainable heretofore.

A further object of the present invention resides in the provision of novel programming means for cross-adding machines. Such programming means will enable the operator to program the sequence of transfers and to selectively route the transfers from any selected accumulator to any other selected accumulator and to also permit the selective transfer of such amounts either additively or subtractively.

A further object of the present invention resides in the provision of controls to automatically terminate transfer cycles selectively after any cycle at the will of the operator and without manual intervention and to provide other machine controls which will thereupon come into action to re-initiate a new calculation pertaining to a new record.

A further object of the present invention resides in an accounting machine with accumulating means capable of being reset during the cycle in which the complement of amounts initially

standing therein are being derived therefrom and entered into another accumulator.

A further object of the present invention is to provide a cross-adding machine of a simple control means in the form of a programming plug-board with programming and selecting controls controlled thereby which will enable the operator to select at will the source or sources of a transfer entry on a particular cycle, the destination or destinations of such entry and the sign or signs of such entry.

A further object of the present invention resides in the provision of a programming control for a cross-adding machine wherein the succession of cycles may be selected at will by the operator.

A further object of the present invention resides in a form of selective control for a cross-adding machine in which a single operator manipulable element such as a plug connection is adapted to effect or render effective all of the desired selections, viz., the source of a transferred entry, the destination of a transferred entry and the sign of a transferred entry and the cycle time in which transfer is to be made.

A further object of the present invention resides in the provision of a simplified programming control for a cross-adding machine.

A further object of the present invention resides in the provision of a cross-adding accounting machine wherein transfer of amounts may be effected from any of a plurality of selected accumulators to any of a selected plurality of other accumulators and wherein transfers may be made in one cycle or on successive cycles or with multiple transfers in the same cycle.

In the drawings:

Figure 1 shows a somewhat diagrammatic view of the various units of the machine and of the driving mechanism therefor;

Fig. 2 is a sectional view taken through the card handling and reading section of the machine;

Fig. 3 is a cam timing diagram;

Figs. 4a, 4b, 4c and 4d, taken together and arranged vertically in the order named, show the wiring diagram of the machine; and

Fig. 5 is an enlarged detail view of the plug-board showing the printed legends appearing thereon. This view is an enlarged view of the plugboard section which is shown somewhat in reduced scale on the circuit diagram.

The machine to which the present invention is shown applied is of a type well known in the art and no detailed mechanical description of the

same is necessary. Reference, however, may be had to United States patents to Daly, No. 2,045,437 and Daly et al., No. 2,088,408, for details of operation and for an explanation of the mechanical parts, card handling and reading mechanisms, accumulators, accumulator drives, punching devices, etc.

The machine, however, is generally shown in Fig. 1 wherein similar reference numerals are used to correspond to the showing on the circuit diagram. The machine comprises four accumulators, designated A, B, C and D. These are driven in the customary manner. A single impulse emitter 10 is provided, driven in the customary manner from the main drive shaft. There is also the usual impulse distributor 11 and cam contacts CC-3, CC-8, CC-9 and CC-10. These are driven in the manner indicated in Fig. 1. Ten FC cam contacts are provided driven in the manner shown in Fig. 1. Cam contacts FC-2, FC-6, FC-7, FC-8, FC-11, FC-17, FC-18, FC-19, FC-20 and FC-21 are timed as shown in the timing diagram (Fig. 3).

The machine includes the customary punching mechanism which is shown in dotted lines on Fig. 1 and which is like the corresponding punch of the Daly patent above referred to. The customary electro-mechanical relay section is dispensed with in the present machine, inasmuch as the multi-contact relays are a purely electrical type.

In lieu of providing individual reset controls on the various accumulators, a single reset control is provided to call into action a reset shaft which, when rotated, resets all of the accumulators concurrently. 12 shows such reset shaft and this shaft is brought into rotation upon energization of the reset magnet 13. The reset drive is obtained in the customary manner from the customary shaft 14 and the customary one-revolution clutch generally designated 15 is adapted to connect the shaft 12 to shaft 14 when accumulator reset is desired. Two reset controlled contacts 16 and 17 are provided. Contacts 16 and 17 both close upon reset.

The machine of the present invention employs stepping switches for controlling the programming of cycles. These are of a type well known in the telephone art and reference may be had to United States patent to Bohlman, No. 1,569,450, which shows and describes a switch of this type. Such switches include a motor magnet which upon energization and de-energization advances a wiper or wipers step by step over a contact bank or banks. They are provided with a release magnet which when energized, allows the wipers to return to normal position under the power of a spring which is wound up upon step by step advance of the wiper. Such stepping switches are customarily provided with so-called off normal contacts or on normal contacts. The stepping switch here used is provided with a pair of contacts which remain closed when the switch arm or wiper is in normal position and which open up in other than normal positions of the switch arm. The stepping switch is also provided with another pair of contacts which are open with the switch arm in normal position and closed when the switch arm is in other than normal position.

Generally, according to the present embodiments, the machine includes four accumulators. All or some of them may receive original entries from the record. Transfer means are provided between the accumulators whereby amounts may be transferred from accumulator to accumulator

and in fact concurrent transfers into two accumulators may be made from two other accumulators in the same cycle or from one accumulator into a plurality of other accumulators. Amounts 5 can also be transferred from accumulator to accumulator either positively or negatively. Suitable control means is provided to select whether a particular transfer is to be of negative or positive character. The machine is intended to operate with one or a plurality of successive transfer cycles after the entry of amounts to provide one or a plurality of successive transfers from accumulator to accumulator. The accumulators further may be used repeatedly in carrying out computations which involve a succession of transfers. The number of different types of computations which the machine is capable of performing is very large. Some typical types will be explained in more detail hereinafter.

20 Generally, as a preliminary to a computation, the operator determines certain sets of facts. First there is a determination from which accumulator or accumulators the amounts are to be derived on each transfer cycle with the computation. There is then a determination of the remaining accumulator or accumulators into which amounts are to be transferred. There is then a further determination of the type of transfer whether it is to be positive or negative. Such 25 determinations are made by the operator before setting up the controls of the machine for any given calculation and further such determinations are made by the operator for each machine cycle. There are also certain rules which the operator must take into account in setting up the controls. These rules follow from the structural 30 limitations and capabilities of the accumulators and may be listed as follows:

1. Only one entry may be made into one accumulator in one step.
2. An entry must not be made to an accumulator from which a transfer is being made in the same step, subject to rule 3.
3. An amount may be transferred from one 45 accumulator to another and also reentered into the first accumulator in the same step, provided that the amount is entered into both accumulators additively or subtractively.

4. The plugging made for each step must have 50 no connection in common with any other step or must be identical with that for another step. A simple illustration will explain the foregoing.

Assume terms A, B, C and D are entered into the respective accumulators. Assume that on the 55 first transfer cycle A is to be transferred to B positively and C to D positively. In this case A and C are the source accumulators and B and D are the destination accumulators. The signs of transfer in each case are positive. For the next 60 step in the calculation the sum of A and B standing in the B accumulator is to be added to the C and D sum standing in the D accumulator. In this event the source accumulator is B, the destination accumulator is D and the sign of the transfer is again positive. Further the transfer cycle is the second transfer cycle. Having thus ascertained the general steps of the computation, the succession of steps, the signs involved in the steps and the routing of the transfer entries, the operator is ready to plug up the machine and condition the controls for the desired calculation. To do this the operator utilizes the novel programming plugboard which plugboard is connected with the respective machine controls so that by merely plugging up this plugboard the 70 75

Machine can be pre-set to perform a calculation involving a great multiplicity of steps and a possible great multiplicity of successive transfers. The plugboard is provided with legends which guide the operator in setting it up.

By the use of the plugboard of the instant invention it is possible by a single plug connection to condition the controls of the machine, first according to source of the transferred entry, second according to destination of an entry to be transferred, third according to sign of the transferred entry and fourth according to the cycle in which the transfer is to take place. The operator does not have to consider separate controls for all of these functions, but merely places one plug connection in place as directed by the legends on the plugboard and this serves to bring all of the controls into operation in the proper relation and at the proper time in the sequence of transfers. When the machine is in use the plugboard remains plugged for a series of computations of a run and after each computation pertaining to a given record is completed, the identical computation is performed pertaining to the following record.

The plugboard will now be generally described.

Generally the plugboard arrangement of the present machine comprises a plugboard which may be considered to have three main sections. The first section is the section for directing and routing the original entries from the record into the accumulators. The third section is a section provided for routing amounts from the accumulators with result amounts therein to the punching apparatus. Such first and third section are sections customarily used in machines of this class. Intermediate the first section and the third section a novel form of board, termed a "programing board" is provided. This section is divided into various steps. Each step corresponds to a machine cycle adaptable for transfer of amounts after the amounts have been originally entered into the accumulator. A multiplicity of such sections are shown and if there is plugging in that section a certain transfer operation will take place during that step or cycle which is related to the section. The programing board in addition to being divided into sections is provided with multiple sockets in each section to permit diverse operations to be performed. Taking a particular section there are a number of sockets at the top bearing a common legend such as "+A." These sockets relate to the accumulator from which an amount is to be transferred and also have a sign characteristic as designated by the + preceding the symbol. It will be noted in Fig. 5 there are four +A sockets and just below them are four sockets with similar reference characteristics *a*, *b*, *c* and *d*. These sockets are the designation sockets and relate to the accumulator to which a transfer is to be effected. For example, if in the first step section a plug connection is made from a +A socket to the *d* socket, there will be a transfer of the amount in the A accumulator to the D accumulator and such transfer will be made positively and it will also be effected in the first step or first transfer cycle following the entry cycle. On the other hand if a like connection from +A to *d* was made in the step two section, this transfer of the A amount positively to the D accumulator would be made in the second transfer cycle and not in the first. On the other hand if on the first step a connection was made

5 from the —A sockets to the *d* socket, the amount standing in the A accumulator would be transferred negatively to the D accumulator and such transfer would take place during the first step following the entry cycle. Assuming now that plug connections are made in the first step section and no plug connections whatsoever were made in the third step section, the machine would then proceed and make the successive calculations required for the first step and for the second step. The machine controls then would come into action at the end of the second step and automatically detect the fact that no calculation whatsoever was set up for the following third step. Under this condition the machine controls would terminate transfer cycles and initiate recording, followed by reset and bring about a card handling operation for entering items from a further record card in the run.

10 20 From the foregoing it will be apparent that the programing plugboard enables the operator of the machine to selectively set the machine to compute according to the sign plus or minus for the desired calculations for any term or terms and the operator can selectively set the programing plugboard to derive an amount from any accumulators as selected by the operator and to enter the amount in any of the other accumulators as selected by the operator.

25 30 The programing board is also multiplied to permit concurrent transfer operations to be brought about in the same cycle, that is to say, an amount can be transferred from A to B when another amount is being transferred from C to D, or from A to B and A to C concurrently, etc. Any desired transfer can be made at the will of the operator except the machine should not be plugged up to attempt to enter two different amounts concurrently into the same accumulator, and further the machine should not be plugged up to enter an amount into the one accumulator while the same receiving accumulator is controlling the transfer of an amount to another accumulator.

Circuit diagram

35 40 45 50 55 60 65 70 75 With pre-punched cards in the card magazine the operator closes switch 20 (Fig. 4d) providing current supply for the main driving motor Z, which drives a D. C. generator 21. This D. C. generator supplies direct current to buses 22 and 23. The start key is now depressed to close start key contacts 24 and complete a circuit from D. C. bus 22, through relay coil M, through start key contacts 24, relay contacts G—1 in the position shown, through cam contacts FC—2 to the 23 side of the line. A stick circuit is established through contacts M—2, and through cam contacts FC—8. Relay contacts M—1 (Fig. 4c) are also closed and a circuit is established through contacts F—1, through the card feed clutch magnet 25 (see also Fig. 1), through cam contacts FC—6, through the stop key contacts 26, through relay contacts M—1, through the punch contacts P—1 now closed and back to the other side of the line. As is customary in machines of this type the start key must be held depressed for the first four machine cycles in starting up on a run or alternatively, it may be depressed and released and then depressed a second time. Starting is prevented until the feed rack of the punch is in the right hand position, this being provided for by the usual P—1 contacts. The first complete card feed cycle on starting up will advance the first card to the position in which the card will

be about ready to pass under the main sensing brushes generally designated 21 (see Figs. 2 and 4a). At the beginning of the second card feed cycle the card traverses the brushes and the amounts from the card are entered respectively into their related accumulators. It will be understood that one or more entries can be made from the card and as here shown four accumulators are provided adapted to receive concurrently four separate entries from the card. With card lever contacts 28 closed, relay coil H (Fig. 4d) will be energized, shifting relay contacts H-1 (Fig. 4a) to reverse position from that shown. As the second card feed cycle ensues the card is carried past the brushes and amounts entered into the accumulators in the usual way.

Briefly, the entry circuits may be traced as follows: Current flows from the D. C. line 23 (Fig. 4a), through H-1, through FC-1, through impulse distributor 11, to the card transfer and contact roll 29, through the brushes 27, to the brush sockets 30 of the entry plugboard. Depending upon the number of entries to be made plug connections are made at this plugboard to the accumulator plug sockets 31A, 31B, 31C and 31D.

For purposes of the present description it will be assumed that the amounts are to be entered in all four accumulators. The circuits from the accumulator plug sockets 31A, etc. extend through a cable 32 (Figs. 4a and 4b) and flow to the accumulator magnets 33A, 33B, 33C and 33D, passing through the contacts 34a of a multi-contact relay having a relay coil 34. The purpose of the relay contacts 34a is to cut off the circuit to the entry plugboard after the amounts have been entered from a card. Relay coil 34 is energized during the entry cycle in the following manner. Relay contacts H-3 are closed during the entry cycle by the energization of relay coil H in the manner previously described. Then upon closure of cam contacts FC-19 (Fig. 4c) a circuit is established to energize the relay coil 34. It will be understood that after the entry or entries are made into the accumulators, this relay coil 34 will become de-energized so that all circuits to the entry plugboard are interrupted. During the operation hand initiating control is cut off in the usual manner, that is, at the beginning of the second card feed cycle the closure of cam contacts FC-11 (Fig. 4d) will cause energization of relay coil G. With relay coil G energized, the three-blade contacts G-1 will be shifted to reverse position interrupting the circuit to the start key contacts 24 but maintaining the circuit to the FC-2 cam contacts. With G energized, contacts G-2 close and establish a stick circuit for coils G and H through either the FC-2 contacts or the card lever contacts 28. As is customary in machines of this type, it may be noted that the making time of cam contacts FC-2 overlaps the time when the card lever contacts 28 open between cards. Relay coils G and H are maintained energized during transfer cycles, since contacts FC-2 are closed during such cycles. The card ultimately passes to the receiving position in the punch, closing contacts 35 (Fig. 4c), energizing relay coil F and shifting F-1 to reverse position. As is customary the punch contacts P-1, P-3 and P-5 are now closed. With P-5 closed, K will be energized and the K-1 contacts will be closed. With punch contacts P-3 closed, the punch clutch magnet 36 will be energized upon closure of cam contacts CC-3, the circuit being through K-1, P-3 to 36, CC-3, through F-1 in the shifted position. The punch motor

latch contacts 37 (Fig. 4d) become latched closed in the usual manner providing current supply for punch driving motor Z-2. The card now advances endwise through the punch in the customary manner.

For purposes of explanation, it will be assumed that it is desired to take four separate entries from a card and to add all of these entries into one final result. For simplicity of explanation the different amounts will be given the same reference character as the accumulator into which the amounts are entered from the card. Thus the problem will be assumed to be A+B+C+D. For this type of operation, the following plug connections are made. At the entry plugboard connections will be made from the brush sockets 27, respectively, to the 31A sockets, 31B sockets, 31C sockets and 31D sockets. This will provide for the entry of the amounts into the respective accumulators A, B, C and D from the card. On the programing section of the plugboard, a plug connection for step one will be made from a socket +A to b. This connection +Ab thus made and identified I +Ab will signify that on the first transfer cycle following the entry cycle as designated by I there will be a transfer of the amount standing in accumulator A in a positive manner to the B accumulator. "b" signifies the receiving accumulator. During the first transfer cycle it is also desired to transfer the amount standing in the C accumulator to the D accumulator. Accordingly, a plug connection is made as follows: I +Cd. This plugging provides for a transfer of the C amount to the D accumulator on the first transfer cycle. At the completion of the first transfer cycle A+B will be standing in the B accumulator and C+D will stand in the D accumulator. It is then desired to get the sum of A+B transferred over into the A accumulator. For this purpose for the second transfer step, a plug connection is made as follows: II +Bd. This plugging will bring about the transfer of the amount from the B accumulator to the D accumulator in a positive manner. Plugging is also provided from final output sockets 38D to sockets 39 which connect to the punch magnets to provide for controlling these punch magnets so as to punch the final result D back on the record card.

For simplicity of explanation, the relay which is called into operation for properly routing transfers will have reference numerals which correspond to the plugging which allows energization of the relay. Thus on a transfer from A to B positively, the relay which would be energized, would be +Ab (Fig. 4c). On the plugboard, in addition to plus plug sockets there are also provided negative sockets so designated by the minus sign preceding the reference numeral, thus -A.

For controlling current supply to the various sections of the programing plugboard at different transfer cycles relays 1, 2, 3, 4, 5, 6 to 18 are provided. The plug sockets for relays 7 to 18 inclusive are not illustrated on Fig. 5, since their relation and wiring will be readily understood from the wiring of the other relays illustrated. The number of these relays correspond to the transfer cycle in which it becomes energized. Thus 1 would signify that the relay is energized in the first transfer cycle, 2 in the second cycle and so on. These relays when energized close contacts 1a, 2a, etc. (Fig. 4c) and afford an input supply into the proper related section of the programing plugboard.

Stepping switch and programing for cycle control

Referring to Fig. 4d, various relays 1, 2, 3, 4, etc., are shown as connected to the contact banks of a stepping switch of the general type shown in the Bohlman United States Patent No. 1,569,450, previously referred to. This stepping switch includes the customary motor or stepping magnet 42 and release magnet 51. Contacts 40a are provided, which are closed when the switch is in normal position and open when the switch is in off normal position. Contacts 40b are open when the switch is in normal position and closed at all other positions. Switch or wiper 43 when in normal position is in circuit with a contact connected to relay coil 50. One step of advance of the switch arm 43 will connect relay coil 1 in circuit, the next step relay coil 2 in circuit and so on. During the entry cycle switch 43 remains in the normal position as shown. During such entry cycle which precedes the transfer cycle, contacts G-4 become closed upon the energization of relay coil G. At about the end of the entry cycle, contacts FC-17 close and a circuit path is established as follows: From line 23, through FC-17, G-4, through the now closed 40a contacts to motor magnet 42 and back to the other side of the line. This will step the switch 43 forward one step of advance and establish a circuit traced as follows: From line 22, through relay contacts 49d now closed, through the switch 43, through the contact pertaining to the 1 relay, through such relay to the other side of the line 23. Transfer operations as will hereinafter be explained now ensue.

During the entry cycle, which precedes the transfer cycle, contacts G-3 (Fig. 4c) become closed energizing relay coil GG which remains energized by virtue of contacts GG-1, the stick circuit going back to line through the FC-21 contacts. With relay GG energized during the entry cycle, contacts GG-5 (Fig. 4d) become closed. At the end of the entry cycle cam contacts FC-18 become closed. Toward the end of the first transfer cycle cam contacts CC-10 close, current then being permitted to flow from line 23, through FC-18, GG-5 now closed, CC-10, through the now closed 40b contacts, through the motor magnet 42 to the other side of the line. This will step the switch forward for the second transfer step and connect relay coil 2 in circuit. A similar action will occur for each successive step of transfer which is required. When all transferring operations are complete a release magnet 51 becomes energized and with this magnet energized the switch arm 43 returns back to normal position under spring action in the customary way. Control of the release magnet is provided for by contacts 49b which are closed in a manner to be subsequently described by the energization of relay magnet 49.

During restoration of the stepping switch, current supply to the switch 43 is prevented by means of contacts 49d which are opened up during the releasing step.

It will be assumed that the four amounts are entered into various accumulators in the manner previously explained and the first transfer cycle is to be initiated. Referring to Fig. 4d, with relay contacts G-4 closed, upon the energization of G in the manner previously explained and upon closure of cam contacts FC-17 a circuit will be completed from the 23 line, through the stepping switch contacts 40a now in the position shown, completing a circuit to energize 75

stepping or motor relay 42. Energization of relay 42 brings about one step of advance movement to stepping switch 43. 43 having advanced one step will connect relay coil 1 in circuit. Energization of relay coil 1 (Fig. 4d) will bring about closure of contacts 1a and provide current supply for the +A plug socket, through relay coil 44 (Fig. 4c). The complete circuit will now be traced, from line 22, through 44, through contacts 1a now closed, to a +A socket, via plug connection from such socket to a b socket, through relay coil +Ab and back to the other side of the line 23. Energization of relay coil +Ab will close the multi-contacts of this relay which are shown to the right of the dotted line coils on Fig. 4a.

The various accumulators A, B, C and D are provided with readouts designated ARO, BRO, CRO and DRO. These readouts are of the customary dual type. One section of such readouts is wired in direct manner to an emitter 10 and the other section of the various readouts is complementarily wired to the emitter. It will be understood that there are two readout devices for each accumulator order and one of these is wired to read out the nines complement of the amount standing on the corresponding order wheel and that the other of these is wired to read out directly the value standing on said wheel. By the use of such a construction it is possible to conveniently derive an amount from the common accumulator for additive entry elsewhere and for subtractive entry elsewhere. Current supply to the emitter 10 is provided through relay contacts T-3 which are normally closed. Upon the first transfer cycle there will be a readout of the amount standing in accumulator A from the ARO readout and such impulses will flow through the multi-contacts of the +Ab relay to a set of lines generally designated 46, which lines it will be seen extend to the 33B accumulator magnets. In this way the amount standing in A is transferred additively into B. During the same first transfer cycle there is also a transfer of the amount standing in C to accumulator D. This transfer entry is permitted because of the energization of relay +Cd which allows impulses to flow from CRO to the group of lines generally designated 47, which extend to the D accumulator (see Fig. 4b). At the end of the first transfer cycle there is an initiating control to initiate the operations pertaining to the second transfer cycle. This initiating control will now be described.

At the end of the entry cycle cam contacts FC-18 become closed and at the end of the first transfer cycle, contacts CC-10 become closed, current is then permitted to flow from line 23, through FC-18, through GG-5, through CC-10, through the now closed contacts 40b to again energize the stepping magnet 42. This energization of the stepping magnet advances the switch 43 an additional step and connects relay coil 2 in circuit. With relay coil 2 energized, relay contacts 2a close and remain closed, during the second transfer cycle and such contacts provide current supply to the +B sockets on the second step section of the programing plugboard and thus energizes the +Bd relay. With relay +Bd energized, the +Bd relay contacts (Fig. 4b) become closed and allow impulses to flow out from BRO, which impulses flow to the 33D accumulator magnets. In this way the amount standing in the B accumulator is transferred over additively into the D accumulator. The

complete final result of the sum of A, B, C and D now stands in the D accumulator and the machine is ready to record this amount upon the record from which the items were derived.

Before describing the recording of this final result upon the record it may be explained that following the second transfer cycle mentioned above, the machine attempts to initiate another cycle and attempts to connect up the third step section of the programing plugboard for control of machine operations. Such third step section of the plugboard is, however, wholly unplugged and this unplugged status of this section provides a control through a test circuit to terminate transfer cycles automatically. This terminating control will now be described.

Following the second transfer cycle described above, the stepping switch 43 is again advanced upon closure of cam contacts CC-10 and the 3 relay becomes energized. Referring now to Fig. 4c, it will be noted that relay coil 44 is in the input circuit to the programing plugboard and under the condition just described with relay 3 energized while there will be an input circuit established to the third step section of the programing plugboard, such circuit will terminate at the plugboard because of the absence of plugs in the third step section. Accordingly, relay 44 will not become energized. With relay coil 44 (Fig. 4c) de-energized, relay contacts 44a (Fig. 4d) remain closed and with such contacts closed upon closure of cam contacts CC-8 a circuit is established as follows: From the 23 side of the line, through FC-18 now closed, through GG-5 now closed, through CC-8, through 44a, to and through relay coil 49. Relay 49 remains energized by a stick circuit through stick contact 49a, relay contacts 50a, to the other side of the line. Upon energization of relay coil 49, relay contacts 49b close and establish a circuit to energize release magnet 51. Contacts 49d open and break the circuit to the relays 2 to 18 inclusive, during the time switch 43 is moving to home position. Energization of release magnet 51 restores the stepping switch 43 to normal zero position (the position shown). The energization of relay coil 49 also closes relay contacts 49c (Fig. 4d) establishing a circuit energizing punch control relay T. Such relay coil T corresponds to the B relay coil of the Daly patent. The T relay remains energized by a stick circuit extending through stick contacts T-2 and contacts K-4 now closed. The energization of relay coil T closes contacts T-1 (Fig. 4c) and establishes a circuit in the usual way to the readout strip of the punch. The plug sockets 39 of the readout strip are connected by plug connections to sockets 38D so that punching of the final result in D proceeds in the usual way by the selective energization of the punch magnets 52. These punch magnets it will be understood are selectively energized under control of the DRO readout. During result punching emitter 10 is isolated from the circuit by the opening of relay contacts T-3 and during result punching the transverse buses extending to the various readouts by the closure of relay contacts T4-13 (Fig. 4a). The energization of relay coil T during result punching also closes relay contacts T14-29 thereby connecting the readout circuits to the plug sockets 38A, 38B, 38C and 38D. By the provision of the construction just described the use of an extra readout section for controlling punching is obviated.

Referring now to Fig. 4d when the stepping switch 43 re-assumes a home position (i. e. the position shown in the drawings) this switch will establish a circuit to energize relay coil 50. The energization of 50 opens relay contacts 50a and de-energizes relay coil 49. Punching proceeds in the usual way and ultimately the usual punch control contacts P-5 close to energize relay coil K. With relay coil K energized, relay contacts K-2 close and a circuit is established from line 23 through FC-18, through K-2, through L-1 now closed to energize reset magnet 13. With 13 energized all of the accumulators are reset to zero. During reset, contacts 16 and 17 become closed, 16 upon closing energizing relay coil L, which upon energizing opens the L-1 contacts to prevent repetition of reset. Relay coil L has a stick circuit through L-2 and the punch control contacts P-2. Contacts 17, upon closing energize relay coil M, the circuit being from line 23, through FC-18, through GG-2 now closed, through 17, through M to line 22. Energization of relay coil M initiates a new card feed cycle upon closure of contacts M-1 in the manner previously described. Relay coil M has a stick circuit through stick contacts M-2, the circuit being completed to line through FC-8 in the usual way.

It will be understood that the illustrated embodiment affords a construction in which nineteen or less transfer cycles may be effected. If the entire nineteen transfer cycles were used, at the end of the last transfer cycle, the switch 43 would be advanced to the unwired last contact. Under this condition all of the relays 1, 2, 3, etc., will remain de-energized and their "a" contacts will remain open. Accordingly, there will be no energization of relay magnet 44 (Fig. 4c) and upon closure of CC-8 (Fig. 4d) relay 49 would be energized terminating operations and bringing about restoration of the stepping switch to normal position in the manner previously explained.

Another calculation will now be described involving subtraction. Let it be assumed that the operator of the machine desires to calculate the following two problems:

$$A+B-D=R-1$$

50 as one result, and

$$B-C+D=R-2$$

as another result. R-1 and R-2 are each to be punched back on to the record. The entry circuits from the brushes will be set up as before, that is, entry circuits will be provided by plugging from 27 to 31A, 31B, 31C and 31D. The programing plugboard for the various steps will be plugged up as follows:

In the first step section a plug connection will be made thus, +Ba. This will provide for a positive transfer of B to the A accumulator. In the second step section a plug connection will be made thus, -Da. This will provide for a negative transfer from D to A and when this transfer is made, the whole result R-1 will be in the A accumulator. Result plugging connections will be made from sockets 33A (Fig. 4a) to the desired sockets 39 (Fig. 4c). For the other computation to obtain the result R-2, plug connections will be made as follows: In the second step section, a connection will be made +Db. This plug connection is made in the second step because in the first step for the other computation, the 75 amount B is being transferred to A and therefore

it is impossible to effect the D to B transfer until after B has been transferred to A for the R-1 computation. For the second computation, in the third step, a plug connection will be made -Cb. The final result will be in the B accumulator and result punching will be provided for by placing plug connections from the 38B sockets to the desired 39 sockets.

When subtractive transfers are effected in the instant machine such transfers are effected by reading out from the readouts, the 9's complement of the amount standing therein entering this amount into the selected accumulator and in the units position causing an elusive 1 to be entered in such accumulator. For providing for the entry of the elusive 1, each of the various accumulators A, B, C and D is provided with an elusive 1 magnet 52. United States patent to Lake, No. 1,976,617, shows the manner in which an elusive one may be entered under an elusive magnet control. This magnet when energized trips the carry latch pertaining to the units order and thus causes an entry of 1 into the units order and this entry with the 9's complementary entry provides for a true complementary into the accumulator. The energization of the elusive 1 magnet is brought about in the following manner: Considering now the negative transfer of D to A, the -Da relay will be energized. Energization of relay coil -Da will close its multi-contacts which include an extreme right hand contact connecting to line 53 (Fig. 4a) which extends to cam contacts CC-9. The right hand contact also connects to a line 54 which, if traced, will be found to extend to the elusive 1 magnet 52A (Fig. 4b).

It seems unnecessary to further trace the operations for this type of problem since they are substantially the same as previously described except that different relays are energized and subtractive transfers are effected at the proper cycle time.

The foregoing description has traced two simple problems which the machine is adaptable for computing. The number of different problems which the machine is capable of computing is numerous. Several of them may be briefly alluded to without detailed circuit description with a mere reference to the cyclic times in which various events take place.

Assume general equations as follows:

$$\begin{aligned} \pm (A \text{ or } B \text{ or } C \text{ or } D) &= R-1 \\ \pm (A \text{ or } B \text{ or } C \text{ or } D) &= R-2 \\ \pm (A \text{ or } B \text{ or } C \text{ or } D) &= R-2 \\ \pm (A \text{ or } B \text{ or } C \text{ or } D) &= R-2 \end{aligned}$$

and assume also a different selection of one or more terms or signs. Thus, as examples, assume

$$\begin{aligned} (a) \quad (B-C) &= R-1 \\ (D+A) &= R-2 \\ (b) \quad (-A+C) &= R-1 \\ (D+C) &= R-2 \end{aligned}$$

Entry plugging will be made in the usual way.

The programing plugging for the first step section of equation (a) will be +Ad and -Cb. This will provide in the first transfer cycle for the transfer of A positively to the D accumulator and for the transfer of C negatively to the B accumulator. This will give the results R-1 and R-2 pertaining to equation (a) above in one

70 transfer cycle or step. For problem (b) program-plugging is as follows: +Cd in the first step section and -Ac in the second step section. Such plugging will provide for the positive transfer of C to the D accumulator in the first step and the negative transfer of A to the C accumulator in the second step.

Consider now general equations as follows:

$$(A \text{ or } B \text{ or } C \text{ or } D) \pm (A \text{ or } B \text{ or } C \text{ or } D) = R-1$$

$$(A \text{ or } B \text{ or } C \text{ or } D) \pm (A \text{ or } B \text{ or } C \text{ or } D) \pm (A \text{ or } B \text{ or } C \text{ or } D) = R-2$$

and with a different section of one or more terms or signs.

As examples of the above assume two problems:

$$(a) \quad B-C+D=R-1$$

$$A+B-D=R-2$$

$$(b) \quad A+B+C=R-1$$

$$A-B-C=R-2$$

For problem (a) above, the programing plugging for the first step would be +Ba, which would bring about the transfer of B positively to A. In the second step section, the plugging would be +Db and -Da. +Db would bring about the transfer of D positively to the B accumulator and the -Da plugging would bring about the negative transfer of D into the A accumulator. In the third step, the program-plugging would be -Cb which would negatively transfer C to the B accumulator, giving a final amount in A=to A+B-D and the final amount in B=B-C+D.

For problem (b) above, the program-plugging for the first step would be +Bc and +Ad and for the second step, it would be +Ca and -Cd. There is no entry from card to D in this problem.

Another typical and illustrative problem might be as follows:

$$(a) \quad B+D=R-1$$

$$B-D=R-2$$

$$C+A=R-3$$

The program-plugging for this calculation would be as follows: In the first step +Ac. This would bring about transfer of the A amount to the C accumulator. In the second step the plugging would be -Aa. This will negatively transfer the A amount back into the same accumulator and thus clear the A accumulator to zero, leaving it available for use in the succeeding steps of the computation. For the third step, the plugging would be +Ba to bring about the transfer of B positively into the now cleared A accumulator. For the fourth step the plugging would be -Da and +Db. This would bring about, during the fourth step the negative transfer of D into the A accumulator containing the amount B and will bring about the positive amount of the D amount to the B accumulator. Then at the conclusion of the computation B-D would stand in A, B+D would stand in B, and C+A would stand in C.

Another illustrative problem which the machine is capable of performing is the following 2A-4B+8C-16D=R-1. In this problem the amounts on the record card would be merely A, B, C and D. For this operation the plugging would be as shown in tabular form below.

	Step	Plugging
I		
II		+Bb -Ba
III		+Cc
IV		+Cc
V		+Ca
VI		+Aa

The effect of step I is to form 2B and 2D in the corresponding accumulators. By step II, 2B is entered negatively into accumulator A to give A-2B, and 2D is entered negatively into accumulator C to give C-2D. Steps III and IV give 2(C-2D) and 4(C-2D) respectively in accumulator C. The effect of step V is that the amount 4(C-2D) in accumulator C is entered additively into accumulator A which then registers the amount A-2B+4C-8D. Step VI gives the final result in accumulator A.

The machine also is capable of computing equations such as A-2B+3C-5D=result. In this case the co-efficient of the term is either even or odd.

The plugging for this problem would be as follows:

Step	Plugging
I	+Bb -Dd
II	+C _a +Dd
III	-B _a +C _c
IV	+C _a +Dd
V	-Dd

It will be noted that the odd units in C and D are dealt with by entering these amounts in the accumulator A before doubling them, and that the doubling of B, the entry of 2B into the accumulator A and the doubling of 2D are so arranged that steps II and IV are identical. The rule 4, pointed out hereinabove is, however, broken for step V which differs from step I. With the circuit arrangement shown the transfer +B to b will also take place, but this does not matter as the performance of a transfer from accumulator B back into itself in step V has no harmful effect. This constitutes an exception to rule 4. which may be restated as follows:

4. The plugging made for each step must have no connection in common with any other step or must be identical with that for another step, unless the unwanted transfer will have no ill effect.

Another typical and peculiar problem may be as follows: Where it is desired to get four different results, this being the maximum capacity of the machine herein shown.

$$B-A=R-1$$

$$B-D=R-2$$

$$C+A=R-3$$

$$D-A=R-4$$

The program-plugging for this problem would be as follows:

Step	Plugging
I	+Ac
II	-Dd
III	-Ad
IV	-Ac
V	+Bb
VI	+Dd

With the above pluggings the sequence of transfer cycles would be as follows: On the first transfer, A would be added to C. On the second transfer D would be subtracted from B in B. In the third step A would be subtracted from D in D. On the fourth step A would be cleared to zero by adding back on this the A amount subtractively. On the fifth step the B-D amount would be taken from B and entered positively in the A accumulator. On the last step the D-A

amount from D is added to the B-D in A to give the desired final result of B-A in the A accumulator.

Other typical illustrative problems showing 5 different kinds of operation which the machine is capable of performing are as follows:

Problem

$$B-C=R-1 \quad D+A=R-2$$

Step	Plugging
I	+Ad -Cb

Problem

$$3B-5C+D-A=R-1$$

Step	Plugging
I	-Cd
II	+Bd +Cc
III	+Bd +Cc
IV	+Bd +Cc
V	-Cd

Problem

$$3B-2A+3D-C=R-1$$

Step	Plugging
I	+Aa +Bd
II	+Ac -Bb
III	-Cb +Dd
IV	+Dd +Dd
V	+Dd

Problem

$$2A-3B+3(D-C)=R-1$$

Step	Plugging
I	+Aa -Cd -Cc
II	-Bb +Dd
III	+Bb +Dd
IV	-Bb +Dd
V	+Cs

Problem

$$3A-3B+5C+7D=R-1$$

Step	Plugging
I	-Bb -Bb +Dc +Dd
II	+Ab +C _a
III	
IV	
V	+Cc
VI	+Cc
VII	+Dd

Problem

$$(B-A)=R-1 \quad B-D=R-2 \quad C+A=R-3 \quad D-A=R-4$$

Step	Plugging
I	+Ac
II	-Dd
III	-Ad -Ac
IV	+Bb
V	+Dd

Problem

$$(B+A)=R-1 \quad C+A=R-2 \quad D-A=R-3$$

Step	Plugging
I	+Ab +Ac -Ad

It seems unnecessary to give further examples because the number of problems is practically infinite.

Referring, however, to the plugboard shown in Fig. 5, it will be noted that there is a break in the showing between step 6 and step 19. In practice, the plugboard would include step sections for the intermediate sections. Likewise on the wiring diagram, relay contacts 1a to 6a only are shown and relay contacts 19a. If further step sections are provided on the plugboard, obviously the extra relay contacts similar to 1a would be provided controlling the input to the other sections of the programing plugboard.

Summarizing, the number of cycles control is dependent upon and controlled by the number of successive sections of the plugboard which is plugged up. This extent of plugging in connection with the stepping switch 43 determines at which cycle relay coil 44 will fail to become energized and thus terminate transfer cycles. The number of times this relay becomes energized under the control of the stepping switch will determine the number of transfer cycles.

Relays such as +Aa, +Ba, -Aa and -Ba, according to their selective energization, determine both the source of a transfer entry and the destination of a transfer entry and also determine the sign of a transfer. The energization of these relays is again dependent upon plugging. One socket determines the source and sign of an amount to be transferred and the other plug socket determines the destination of the transferred amount.

What I claim is:

1. An accounting machine comprising a plurality of accumulators, means to transfer amounts additively or subtractively from accumulator to accumulator, a plurality of selectively operable routing means for selectively routing transferred amounts from selected source accumulators to selected receiving accumulators, one set of said routing means being provided for additive transfers and another set being provided for negative transfers, a plurality of machine cycle control means for bringing said routing means into operation to enable transfer operations to be effected in a selected one of a succession of machine cycles, means for causing successive operation of said last named means in successive machine cycles, fixed wiring in the machine for routing transferred amounts from selected source accumulators through the routing means to selected receiving accumulators, each of said routing means and the fixed wiring co-operating therewith invariably routing an amount from a determined source accumulator to a determined receiving accumulator and all of routing means with the fixed wiring providing for each possible different transfer between the various source accumulators and the various receiving accumulators, a programing plugboard having different sets of sockets connected to the different machine cycle control means and other sets of sockets connected individually to each and all of the routing means, and a common single plug wire adapted upon insertion in a selected single socket of the different sets of sockets connected to the machine cycle control means and upon insertion in one of the sockets connected to a routing means to connect a machine cycle control means and a routing means for conjoint operation upon operation of the machine cycle control means, said single plug wire when selectively inserted by the operator con-

5 currently selecting and rendering effective for subsequent action routing means for a selected source and selected destination accumulator and for a selected sign of transfer and for also selecting which one of the plurality of machine cycle control means operating in an operated selected cycle is to be effective to cause operation of the routing means for a transferring operation.

10 2. In a cross-adding machine having a plurality of accumulators provided with positive and negative readout means, and means for transferring amounts under control of said readout means, from accumulator to accumulator in one or more successive machine cycles, machine cycle control means for bringing about transferring by the transfer means in one or more successive machine cycles, a plurality of relay routing means which when selectively energized selectively route transfers from related selected accumulators to related selected accumulators, the combination wherein there are a plurality of the aforesaid machine cycle control means each related to a different successive cycle, means for causing the successive operation of said last named means in successive machine cycles, means for selecting the machine cycle control means which are to be effective whereby the machine cycles in which one or more transfers are made may be selected, said last mentioned means comprising a programing plug board having a plurality of sections allotted to related different successive machine cycles, each section having sockets commonly connected to the related machine cycle control means of said plurality of machine cycle control means and sockets individually connected to related relay routing means, each section when plugged with a plug connection connecting the common sockets and a relay socket being adapted to connect the related machine cycle control means to the related relay routing means whereby operation of the control means causes operation of the relay routing means.

15 3. The invention according to claim 1, wherein the programing plug board is made up of a plurality of successive sections, each section having a plurality of sockets connected to the related machine cycle control means and each section having a set of sockets individually connected to each of the routing means, said multiple section board and multiple sockets in each section enabling the operation by the insertion of a plurality of plug connections, one only for each transfer step of a computation, to select and connect a plurality of routing means to machine cycle control means for a plurality of transfers and to also enable the operator to select the cycle time of each transfer by the machine cycle control means which is or are connected, said plurality of insertable plug wires also enabling the operator to connect and condition the machine cycle control means to cause a plurality of transfers which may be in a desired selected order of succession or concurrence at will.

20 4. A machine according to claim 2, wherein the relay routing means includes routing means for routing transfers negatively under control of the negative readout means of the accumulators and other routing means for routing transfers positively under control of the positive readout means of the accumulators, and wherein the sockets of the programing plug board include sockets connected to the routing means for negative transfers and other sockets connected to the

routing means for positive transfers whereby one or the other of said sockets when plugged with a single plug connection to one of the common sockets may selectively determine a positive or negative transfer.

5. In a cross-adding machine having a plurality of accumulators and means for transferring amounts from accumulator to accumulator in one or more successive machine cycles, machine cycle control means for bringing about transferring by the transfer means in one or more successive machine cycles, a plurality of relay routing means which when selectively energized selectively route transfers from related selected accumulators to related selected accumulators; the combination wherein there are a plurality of the aforesaid machine cycle control means each related to a different successive machine and transfer cycle, means for causing operation thereof in successive machine cycles, and wherein the plurality of accumulators include a plurality of source accumulators with readouts and a plurality of receiving accumulators, each of said relay routing means having multi-contacts, fixed wiring connecting said multi-contacts to the receiving accumulators and to the readouts of the source accumulators, each routing relay when energized invariably connecting a determined source accumulator to a determined receiving accumulator through a portion of said fixed wiring, said different routing relays and the fixed wiring to their multi-contacts providing for each possible different transfer between the various source accumulators and various receiving accumulators, a programing plug board arranged in multiple sections, each related to a different transfer cycle, and each section having sets of sockets commonly connected to the machine cycle control means for the related section, each section having further sockets individually connected to each of the different relay routing means, said former and latter sockets of each section when plugged with one or more plug connections in a section being adapted during the related transfer cycle to make the related machine cycle control means effective to bring about energization of the one or more relay

routing means whose sockets are plugged upon operation of said machine cycle control means.

6. In a cross-adding machine with a plurality of accumulators, means for transferring amounts from accumulator to accumulator, machine cycle control means for bringing about transferring by the transfer means in one or more successive transfer cycles, the combination wherein the machine cycle control means comprises a stepping switch with a plurality of stepping switch relays one for each successive transfer cycle and which relays are selectively successively energized upon each step of advance of the stepping switch, cyclically operable means for causing step by step advance of said switch, an operation determining master relay which is variably influenced to afford further transfer operations or to terminate transfer operations, means for selectively controlling said operation determining master relay under the conjoint control of the successively energized stepping switch relays and manually settable selecting means, said manually settable selecting means comprising a multi-section programing plug board, having a series of successive sections, each related to a stepping switch relay and to a particular successive transfer cycle, each section further having plug sockets which when plugged with a plug connection or connections, with the stepping switch relay pertaining to said section energized, determine a condition of the master relay to afford further transfer operations, each said section when wholly unplugged determining a terminating control condition of the master control relay, whereby the number of successive transfer cycles is determined by the number of successive sections of the programing plug board which are plugged and whereby the first unplugged section determines a suppression of transfer operations in the related machine cycle.

7. A machine according to claim 6 wherein means are provided controlled by the operation determining master relay when it is in its terminating control condition for causing the stepping switch to be restored to normal position.

JAMES W. BRYCE.
